UNITED STATES PATENT OFFICE

121,519

DESIGN FOR A TOOTHBRUSH OR THE LIKE

Conrad D. Mastrud, Chicago, Ill.

Application April 22, 1940, Serial No. 91,849

Term of patent 14 years

To all whom it may concern:

Be it known that I, Conrad D. Mastrud, a citizen of the United States, residing at 5510 West Walton Street, Chicago, Illinois, in the county of Cook and State of Illinois, have invented a new, original, and ornamental Design for a Toothbrush or the like, of which the following is a specification, reference being had to the accompanying drawing, forming a part thereof.

I claim:

The ornamental design for a toothbrush or the like, substantially as shown.

CONRAD D. MASTRUD.
